CLAIM

The ornamental design for a cosmetic container for lipstick and the like, substantially as shown.

DESCRIPTION

FIG. 1 is a perspective view of a cosmetic container for lipstick and the like showing my new design;

FIG. 2 is a top plan view shown in FIG. 1;

FIG. 3 is an elevational view shown in FIG. 1 from a
front side;

front side;

FIG. 5 is an elevational view shown in FIG. 1 from the side opposite that of FIG. 3; and

FIG. 6 is a bottom plan view shown in FIG. 1.
